United States Patent Office

Des. 207,260
Patented Mar. 28, 1967

207,260

FIRE EXTINGUISHER

Jakob Jensen, Roskilde, Denmark, assignor to The Ansul
Company, Marinette, Wis., a corporation of Wisconsin

Filed May 17, 1966, Ser. No. 2,330

Term of patent 14 years

(Cl. D16—2)

FIG.-1

FIG.-2

FIG.-3

FIG-4

FIGURE 1 is a perspective view of the fire extinguisher of my invention;

FIGURE 2 is a side elevation;

FIGURE 3 is a top plan view; and

FIGURE 4 is a fragmentary end elevational thereof. I claim:

The ornamental design for a fire extinguisher, as shown.
